PORTABLE ELECTRONIC WHEEL LOAD SCALE

Wilson Wayne Rairigh, Baltimore, Md., assignor to
Loadometer Corporation, Baltimore, Md., a corporation of Maryland

Filed Mar. 10, 1966, Ser. No. 1,393

Term of patent 14 years

(Cl. D52—10)

FIG. 1

FIG. 2

FIG. 3

FIG. 4

FIG. 5

FIG. 6

FIG. 1 is a perspective view of the portable electronic wheel load scale showing my new design;

FIG. 2 is a plan view looking downwardly at the top thereof;

FIG. 3 is an elevational view of one side thereof;

FIG. 4 is an elevational view of the opposite side thereof;

FIG. 5 is a front elevational view of the front thereof; and

FIG. 6 is an elevational view of the rear of the wheel load scale.

The essential features of the scale are shown in solid lines.

I claim:

The ornamental design for a portable electronic wheel load scale, as shown and described.
